Patented Apr. 29, 1958

182,672

ALARM STATION HOUSING

Adam S. Korabowski, Springfield, Mass., assignor to The Standard Electric Time Company, Springfield, Mass., a corporation of Connecticut

Application September 26, 1956, Serial No. 43,107

Term of patent 14 years

(Cl. D72—1)

Fig. 4.

Fig. 1.

Fig. 2.

Fig. 3.

Fig. 1, is a front elevational view of an alarm station housing embodying my new design;

Fig. 2, is a side elevational view of the alarm station housing shown in Fig. 1;

Fig. 3, is a rear elevational view of the alarm station housing shown in Fig. 1; and

Fig. 4 is a perspective view of the alarm station housing shown in Fig. 1.

I claim:

The ornamental design for an alarm station housing, as shown.
